(57) **CLAIM**

The ornamental design for a footwear outsole, as shown and described.

DESCRIPTION

FIG. 1 is a bottom perspective view of a footwear outsole showing my new design;

FIG. 2 is a bottom plan view thereof;

FIG. 3 is a right side elevational view thereof;

FIG. 4 is a left side elevational view thereof;

FIG. 5 is a front elevational view thereof; and,

FIG. 6 is a rear elevational view thereof.

The broken-line oval in FIGS. 1 & 2 forms the boundary of the design. The broken lines and the area within form no part of the claim.

The broken lines showing a boot throughout the views illustrates the portion of the design that forms no part of the claim.
